UNITED STATES PATENT OFFICE.

PATRICK J. MADDEN, OF CHICAGO, ILLINOIS.

PIPE-CO尤LING.

1,089,656.

Specification of Letters Patent. } Patented Mar. 10, 1914.

Original application filed December 21, 1907, Serial No. 407,604. Continuation application filed July 27, 1909, Serial No. 509,913. Divided and this application filed September 30, 1911. Serial No. 652,101.

To all whom it may concern:

Be it known that I, PATRICK J. MADDEN, a citizen of the United States, residing at Chicago, in the county of Cook and State of Illinois, have invented certain new and useful Improvements in Pipe-Couplings, of which the following is a specification.

The present invention relates more particularly to means for coupling or connecting the end of a pipe or equivalent device with a plumbing fixture having through it an opening for the passage of water, so that the pipe and opening of the fixture register with each other and the joint between them is made water tight.

The object of the invention, generally stated, is to provide, for this purpose, improved means for connecting or coupling the parts together—improved in the respects that the coupling (as it will hereinafter be called) forms an efficient water tight joint; prevents any movement of the parts relatively to each other in any direction; affords a seat for the valve for controlling the opening of the receptacle; has but few parts of simple construction that easily and quickly assemble or disassemble and is of great strength and durability.

To these ends the invention consists in the features of novelty that are hereinafter described with reference to the accompanying drawing which is made a part of this specification and in which:

Figure 1 is a view, partly in elevation and partly in vertical central section, of a lavatory having a pipe connection embodying the invention. Fig. 2 is a section of some of the parts thereof on an enlarged scale.

For the purposes of illustration, I have shown the invention as embodied in a coupling for connecting a lavatory bowl with its waste outlet pipe or trap, but it will be understood that the invention is equally applicable to a large variety of plumbing fixtures and that it may be used at either the outlet or the inlet opening of the fixture. With this understanding the following description will be confined to that specific application of the invention which is shown in the drawing.

A represents the bowl proper of a lavatory, the bottom of which is provided near the back with an opening a guarded by a strainer. Behind the back of the bowl is a vertical chamber A' which extends from the

under side of the horizontal top slab A² at the back of the bowl downward to a level below the bottom of the bowl, and the bottom of this chamber is extended forward beneath the bowl to a point in front of the opening a to form a passage a' through which the interiors of the bowl and the chamber are in constant open communication. The bowl A, the chamber A' and the passage connecting them taken together constitute what is herein called the "receptacle."

The bottom of the chamber A' (i. e. the bottom of the receptacle) is provided with an opening a² for the outlet of the contents of the receptacle. The circular wall of this opening flares upward and outward, and on its under side the bottom of the receptacle is countersunk around the opening, the outer circular wall a³ of the countersink being flared downward and outward, and providing a bearing surface presented inward, toward the opening. Within the opening is arranged a thimble comprising a flaring portion B and a cylindrical portion B'. The flaring portion is complementary to and bears firmly upon the flaring wall a² of the opening and its inner flaring face affords a seat for the valve for controlling the opening. This valve consists of a rubber ring B² of appropriate shape surrounding a tube B³ and held in place thereon by a nut B⁴ having threaded engagement with the tube. The tube B³ occupies the chamber A' and passes through an opening at the top thereof, its upper end being provided with a suitable knob for manipulating it. It performs the double function of an overflow and a stem for the valve B² in customary manner. The cylindrical portion of the thimble extends into the countersink and is externally threaded. On to it is screwed a ring C which bears against the bottom of the countersink so that when screwed home it holds the thimble firmly in place and is itself firmly held in place by the thimble. The periphery of the ring is chamfered reversely to the flaring wall a³ of the countersink to provide a bearing surface, so that the two together form a groove of substantially V-shape in which fits one side of an elastic packing ring D of substantially diamond-shape in cross section. The other side of the packing ring fits in an annular V-shaped groove formed in a flange e carried by the vertically presented open end of a pipe E.

With the parts thus constructed and arranged, a water tight joint between the receptacle and pipe may be made by forcing them toward each other and compressing the packing ring D, and so far as the present invention is concerned, this may be done by any suitable means. The means shown in the drawings consist of a screw F engaging the pipe, a nut F¹ supporting the screw and 5 a housing A³ supporting the nut, the housing being integral with the bowl, and so shaped as to cover the end of the pipe. With this arrangement, the pressure provided by tightening the screw reacts in opposite directions against the receptacle and 10 pipe with a tendency to force them toward each other and compress the packing ring, but, the pipe being supported, (as presently described) so as to be incapable of any vertical movement, the tightening of the screw, in fact, draws the bowl downward toward the pipe. Thus the pipe may be made to 15 support the receptacle, either wholly or partially. But the housing and the means for supporting the receptacle, just described, 20 form a part of the subject matter of my Patent No. 897,914, granted September 8, 1908, and are not claimed broadly in this application.

When the earthenware parts of the fixtures come from the baking oven the distance between the opening a² and other parts of the baked article varies more or less in different articles, because of the impossibility of 25 molding and baking earthenware articles of complicated formation with such accuracy and perfection that all of them will be exactly alike in all of their measurements, the differences being due in part to inaccuracies in molding and in part to inequalities of expansion and contraction, and with 30 an article of the particular class shown in the drawing the position of the opening a² with relation to the other parts of the article may also be varied by reason of the common practice of dressing off the back surface which is intended to bear flat against the supporting wall or other support. It is 35 therefore necessary to provide means for adjusting the up-turned open end of the pipe E relatively to the wall in order that it may be brought to register accurately with the opening a², the distance of which latter from the supporting wall will vary in different fixtures, owing to the causes above mentioned. To this end a nut H on an externally threaded horizontal portion E' of the pipe-section E is adjusted to such position 40 that when the open end of the pipe is in register with the opening of the receptacle, the nut bears against the outer face of the wall; an internally threaded pipe-section, I, which forms a continuation of the pipe-section, E, fits, snugly, a horizontal opening 45 through the wall and is screwed on to

the threaded portion E' of the pipe-section E until it compresses between its end and the nut H an elastic gasket, J, and a nut K is turned on to the externally threaded projecting end of the pipe-section, I, until it bears firmly against the rear face of the wall, whereby the wall is firmly clamped between the two nuts and the pipe, comprising the pipe-sections, E and I, firmly held against either vertical or horizontal movement relatively to the wall.

The vertically presented end of the pipe, E, has an upwardly projecting annular lip, e', and the ring C has in its under side a countersink, c, into which the lip projects, said countersink resulting in an inwardly presented bearing surface which encircles the lip, the arrangement being such that any considerable lateral movement of the upper end of the pipe relatively to the receptacle, or conversely, any considerable movement of the receptacle relating to the pipe will be prevented by the contact of the lip and the inwardly presented bearing surface.

At the top side of the back or wall slab A⁶ the rib or raised portion A⁵ is undercut to provide an overhanging lip A⁹, the shoulder resulting from the sloping inner face of which is adapted to rest upon a correspondingly inclined seat on a bracket L carried by a plate M secured to the wall G. A rubber packing N is interposed between the bracket and shoulder for the purpose of lessening the liability of breaking the earthenware. This bracket (or these brackets 50 where more than one are used, as in the present case, where one is used on each side of the center of the fixture) forms the main support for the fixture, and to the extent that it supports the fixture the waste pipe is relieved of the weight of the fixture, albeit the waste pipe could support the entire weight of the fixture if desired or if perchance, an error in assembling the parts should result in bringing the bracket so low 55 down that the shoulder on the back of the wall slab, A⁶, did not come to a firm seal on the bracket. But if the parts are properly assembled the weight of the fixture will be sustained in part by the bracket and in part by the waste pipe. Furthermore by reason of the sloping shape and consequent interlocking of the bracket and the shoulder, the bracket will prevent the fixture from moving horizontally away from the wall, 60 and this is also done by the waste pipe so that there are two means for accomplishing this object.

This is a division of my application for a patent for improvements in plumbing fixtures, filed July 27, 1909, Serial No. 509,913.

The subject matter of the present application was originally shown and described in my application filed Dec. 21, 1907, Serial No. 407,604.

What I claim as new is:

1. In a pipe coupling, the combination with a receptacle having through it an opening for the passage of water, and a pipe having an open end registering with said opening, of means for coupling the receptacle and pipe together, said coupling means having on the receptacle an annular bearing surface, surrounding its opening and presented inward, a thimble passing through the opening of the receptacle, a ring having threaded engagement with the thimble and providing a bearing surface presented outward, said bearing surfaces being spaced apart to provide an annular groove between them, a packing ring occupying said annular groove and a corresponding groove in the pipe, and means for forcing the receptacle and pipe toward each other.
2. In a pipe coupling, the combination with a receptacle having through it an opening for the passage of water, and a pipe having an open end registering with the opening of the receptacle, means for coupling them together, said coupling means having a thimble extending through said opening and provided with a valve seat presented upward, a ring having threaded engagement with the thimble and having in its under side a countersink, resulting in an inwardly presented bearing surface, the pipe being provided with an annular lip extending into said countersink and means for forcing the receptacle and pipe toward each other.
3. In a pipe coupling, the combination with a receptacle having through it an opening for the passage of water, the receptacle being countersunk around the opening providing a bearing surface presented inward, a ring located in said countersink and having a bearing surface presented outward, a space being left between said bearing surfaces to form an annular groove, a thimble supported by the receptacle and extending through the opening thereof, said thimble and ring having threaded engagement with each other, a packing ring interposed between the receptacle and pipe and occupying the groove aforesaid and a corresponding groove with which the pipe is provided.
4. In a pipe coupling, the combination with a receptacle having an opening through it, said receptacle being countersunk around said opening providing a bearing surface presented inward, a ring located in said countersink and providing a bearing surface presented outward, a space being left between said bearing surfaces to form an annular groove, a thimble supported by the receptacle and passing through its opening, said thimble and ring having threaded engagement with each other and the ring being provided with a bearing surface presented inward, a pipe having an open end registering with the opening of the receptacle and having an annular lip encircled by said inwardly presented bearing surface of the ring, a packing ring interposed between the receptacle and pipe and occupying the groove aforesaid and a corresponding groove formed in the pipe, and means for forcing the pipe and receptacle toward each other.
5. A plumbing fixture having a receptacle provided through its bottom with an opening for the discharge of water, a pipe having an open end presented upward and registering with said discharge opening, said pipe having also a horizontal portion adapted to extend through an opening formed through a supporting wall, means for coupling together the receptacle and the upwardly presented end of the pipe and preventing their movement relatively to each other, said horizontal portion of the pipe being made up of an inner section screw threaded on its exterior and an outer section screw threaded on both its exterior and interior, a nut turned on to the outer section and adapted to engage the rear face of the wall, a nut turned on to the inner section and adapted to engage the front face of the wall, and a packing ring surrounding the inner section between the nut last aforesaid and the end of the outer section.
